GAS LIGHTER

Louis Laghetto, Somerville, Mass., assignor to
Albert B. Tenney, Lexington, Mass.

Application February 20, 1934, Serial No. 712,175

6 Claims. (Cl. 175—115)

This invention relates to an automatic lighting and extinguishing apparatus for burners, and as illustrative of its utility is herein shown as applied to a conventional burner of the type used 5 in gas ranges, ovens, etc.

The principal object of the invention is to provide an apparatus of the aforesaid type which is of simple construction, reliable and efficient in operation, which can be easily built into or assembled with any of the conventional types of gas burners at a relatively low cost, and which dispenses with the necessity of using a pilot which remains lighted when the burner is not in use.

Other objects are to provide a lighter mechanism which is operative automatically to relight the burner in event the flame is blown out or otherwise accidentally extinguished, thus insuring a lighted jet so long as the gas is turned on; and to provide a lighter which is automatically operative in conjunction with and in response to the operation of the control means for opening and closing the gas line.

Further objects relate to the construction and operation of my new apparatus and will be apparent from a consideration of the following description and accompanying drawing which exemplifies one embodiment of the invention chosen for the purpose of illustration.

In the drawing:

30 Fig. 1 is a top plan view, with parts broken away and shown in section, of a gas burner embodying my invention;

Fig. 2 is a fragmentary side elevation with parts shown in section; and

35 Fig. 3 is a schematic wiring diagram showing the association of the different parts of the apparatus.

Referring to Fig. 1, the numeral 10 designates a conventional two-burner gas range which comprises a main supply line 11 and branch lines 12 and 13 to which are connected gas burners 14 and 15, respectively. The branch lines 12 and 13 are furnished with manually operated valves 16 and 17, respectively, by means of which the gas supplied to the respective burners may be regulated or adjusted so as to produce a flame of the desired size. The entire range may be supported on any suitable structure. Suitable valve means are provided for opening and closing the main 50 line 11 so as to control the gas supply, and to this end I preferably employ an electrically operated valve such, for example, as a solenoid or magnetic gas valve 20 which normally holds the line 11 closed.

55 Pilot tubes 24 and 25 are connected at one end

to the branch lines 12 and 13, respectively, between the manually operated valves 16 and 17 and the burners, and their open ends are juxtaposed to the burners as shown in Figs 1 and 2. Adjacent to its open end each pilot tube is provided 5 with a series of longitudinally extending, spaced apertures 28 which define a gas trail (indicated by the arrows in Fig. 2) leading up to its open end.

A lighter, designated by the numeral 30, is mounted between the burners 14 and 15, as shown 10 in Fig. 1. The lighter 30 comprises a casing 31 having a removable cover or cap 32 (Fig. 2), an electrical ignition element 33 disposed within the casing, and a pair of tubular members or flash tubes 35 and 36 extending outwardly toward the 15 pilot tubes 24 and 25, respectively, to a point closely adjacent to one of the apertures 28. The inner ends of the tubular members are preferably flared so as to embrace a larger area of the ignition element and thus direct a greater portion of 20 the heat created thereby outwardly.

In the embodiment herein shown the lines 40 and 41 are connected directly to power supply 25 lines 43, and the solenoid of valve 20 and the ignition element 33 are connected in series across the lines 40 and 41, as shown in Fig. 3. A manually operable switch 44 is connected in series in the line 41 and is operable to open and close the circuit through lines 40 and 41, thus controlling the operation of both the valve 20 and ignition 30 element 33. If desired, an automatically operated switch such as a "Timostat" 45 may be connected in series in either the line 40 or 41 and, as here shown, the "Timostat" 45 is connected in the line 41 between the manually operated switch 44 and the supply line 43. As both the "Timostat" 45 and switch 44 are connected in series 35 in the line 41 and hence control the flow of current through the circuit 40—41, the "Timostat" 45 may be used either in place of, or in conjunction with the manually operated switch 44. As the "Timostat" herein shown is operated by an electric motor (rather than by a spring-wound mechanical motor), it is provided with a separate circuit which includes a line 47 connected to the line 41 and a line 48 connected to the line 40. If desired, a pilot light 42 may be connected to the line 40 and to the line 41 at a point between the switch 44 and ignition element 33 to indicate 40 whether the switch 44 and/or "Timostat" 45 is 45 open or closed.

When the switch 44 and "Timostat" 45 are closed, current flows through the line 40, the solenoid of the valve 20, the ignition element 33 and the line 41, and also through the lines connecting 50 55

the pilot light 42, but in event the ignition element burns out, or when either the switch 44 or "Timostat" 45 is open, the flow through the circuit is broken and the valve 20 automatically closes the 5 gas line 11.

The operation of the apparatus is as follows: When the switch 44 and/or "Timostat" 45 holds the circuits 40 and 41 open, the valve 20 is closed and the ignition element remains dead. With the 10 manually operated valves 16 and 17 open and adjusted so as to permit the desired flow through the lines 12 and 13, the switch 44 or "Timostat" 45 may be operated to close the circuits 40 and 41, whereupon the solenoid of the valve 20 becomes energized, thus opening the supply line 11 and permitting a flow of gas to the burners 14 and 15 and also a flow through the pilot tubes 24 and 25. Simultaneously with the operation of the 15 valve 20, the ignition element 33 comes into operation and discharges heat into the tubular members 35 and 36. Part of the gas flowing through each of the pilot tubes escapes through the apertures 28 and provides a gas trail between the open end of the tubes 24 and 25 and the outer ends of 20 the tubular members 35 and 36. The tubular members 35 and 36 are effective to conduct a portion of the gas thus escaping inwardly toward the ignition element 33 where it comes in contact with the heat discharged by the element 33 25 and consequently becomes ignited. The ignited gas within the tubular members, back fires or flashes back and lights the gas trail on the exterior of the tubes 24 and 25 and in turn the gas trail lights the burners and maintains them lighted as long as the valve 20 remains open. In event either burner flame and/or its associated pilot flame blow out or otherwise become accidentally extinguished, the ignition element and gas trail become effective to relight 30 both the pilot and burner in the manner previously explained.

With the construction and arrangement herein shown, there is no necessity of maintaining a lighted pilot when the burners are not in use, and 45 either of the burners, together with its pilot, may be shut off by the manually operated valve associated therewith, without effecting the operation of the other burner. Furthermore, when either a "Timostat" or the like is used in place of the 50 manually operated switch 44, the operation of the burners is entirely automatic and the "Timostat" may be set so as to light the burners at any desired time, and after the expiration of a predetermined period automatically shut them off. Moreover, 55 as the operation of the valve 20 is subject to the same control as the ignition element, there is absolutely no danger of turning on the gas without turning on the ignition, and if for any reason the ignition element should fail to function, i. e., 60 remain or go dead, then no current will flow through the solenoid of valve 20, and consequently no gas will be supplied to the burners 14 and 15. Thus the entire apparatus may be operated with perfect safety. While I have 65 shown and described one desirable embodiment of the invention, it is to be understood that the present disclosure is for the purpose of illustration only, and that various changes in shape, proportion and arrangement of parts, as well as 70 the substitution of equivalent elements for those herein shown and described, may be made without departing from the spirit and scope of the invention as set forth in the appended claims.

I claim:

75 1. Apparatus of the class described comprising

a supply line, a gas burner connected to said supply line, an electrical valve in said supply line, a pilot tube connected to said supply line between the valve and burner, the open end of said pilot tube being juxtaposed to said burner, said pilot tube having a longitudinally extending series of spaced apertures adjacent to its open end providing a gas trail when said valve is open, and ignition means comprising an electrical ignition element spaced from said burner and a tubular member extending from said ignition element to one of said apertures, said tubular member being effective to conduct gas from said gas trail to the vicinity of said ignition element, said ignition element being operative simultaneously with the opening of said valve to ignite and maintain ignited gas escaping from said pilot tube.

2. Apparatus of the class described comprising a supply line, a gas burner connected to said supply line, a normally closed valve in said supply line, a pilot tube connected to said supply line between the valve and the burner, the open end of the pilot tube being juxtaposed to said burner, said pilot tube having a longitudinally extending series of spaced apertures adjacent to its open end providing a gas trail when said valve is open, an electric circuit including a manually operated switch for opening and closing said circuit, an electrical ignition element connected in series in said circuit and spaced from said burner, 25 a tubular member extending from said ignition element to one of said apertures in said pilot tube, said tubular member being effective to conduct gas from said gas trail to the vicinity of said ignition element, and a solenoid connected 30 in series in said circuit and operative to open said valve when said circuit is closed, said ignition element being effective upon the closing of said circuit to ignite and maintain ignited gas escaping from said pilot tube.

3. Apparatus of the class described comprising a supply line, a plurality of heating units each including a main burner and a pilot burner disposed adjacent to the main burner, a branch line connecting the burners of each unit with said supply line, a normally closed main valve in the supply line, a manually operated valve in each branch line, the pilot burners being connected to said branch lines between their associated main burners and the manually operated valves, an electrical circuit including a switch for opening and closing said circuit, electrically operated means connected in said circuit for opening said main valve, an electrical ignition element connected in said circuit in series with said electrical operating means, said ignition element being spaced from said units, and means operative when said main valve is open to conduct unignited gas escaping from the burners of the several units to the vicinity of said ignition element to cause 60 said gas to become ignited and ignite and maintain ignited the burners of each unit whose manually operated valve is open.

4. Apparatus of the class described comprising a supply line, a plurality of heating units each including a main burner and a pilot burner disposed adjacent to the main burner, a branch line connecting the burners of each unit with said supply line, a normally closed main valve in the supply line, a manually operated valve in each branch line, the pilot burners being connected to said branch lines between their associated main burners and the manually operated valves, an electrical circuit including a switch for opening and closing said circuit, electrically operated 70

means connected in said circuit for opening said main valve, an electrical ignition element connected in said circuit in series with said electrical operating means, said ignition element being spaced from said units, and a flash tube extending from each unit to said ignition element, the flash tubes being constructed and arranged to conduct unignited gas escaping from one of the burners of their respective units to the vicinity of the ignition element where said gas becomes ignited and flashes back, thereby igniting and maintaining ignited the burners in each unit from which gas is escaping.

5. Apparatus of the class described comprising a supply line, a gas burner connected to said supply line, a valve in said supply line, electrical means for operating said valve, a pilot adjacent to said burner and connected to said supply line between said burner and valve, a stationary electrical resistance ignition element spaced from said pilot, said ignition element being connected with said electrical means so that when said valve is open the ignition element is turned on, and stationary means operative when said valve is open

10 to conduct gas escaping from said pilot to the vicinity of said ignition element thereby to cause said gas to become ignited and to then conduct the flame to said pilot to ignite the gas escaping therefrom.

6. Apparatus of the class described comprising a supply line, a gas burner connected to said supply line, a valve in said supply line, electrical means for operating said valve, a pilot adjacent to said burner and connected to said supply line 15 between said valve and burner, a stationary electrical resistance ignition element spaced from said pilot, said ignition element being connected with said electrical means so that when said valve is open the ignition element is turned on, and a stationary flash tube between said pilot and said ignition element, said flash tube being operative to conduct unignited gas escaping from said pilot towards said ignition element to cause said gas to become ignited and flash back so as to ignite 20 and maintain ignited said pilot when said valve is open.

LOUIS LAGHETTO.
